UNITED STATES PATENT OFFICE

ALFRED C. FARR, OF UPLAND, INDIANA, ASSIGNOR OF ONE-FOURTH TO NO-GREEF PRODUCTS, INCORPORATED, OF MUNCIE, INDIANA, A CORPORATION OF INDIANA.

DOOR-OPERATING MECHANISM

Application filed December 30, 1927. Serial No. 243,662.

My invention relates to door operating devices and has for its object to provide a sectional door adapted for upward swinging movement into a folded position and ar-

5 ranged for actuation by either a manual operable lever or a crank lever operable through contact with the wheels of a vehicle.

By providing an optional mode of operation for the device, the same is equally well 10 adapted for use in connection with warehouse doors or the like by utilizing the manual operable lever or with respect to garage doors arranged for automatic operation upon the vehicle wheel engaging the crank lever.

15 A further object of the invention is to provide an apparatus of this character of simple and practical construction, efficient and reliable in performance, in which the parts required for the door are reduced to a minimum, 20 thereby enabling the manufacture at a relatively low cost and which is otherwise well adapted for the purposes for which the same is intended.

Other objects and advantages reside in 25 the special construction and combination of the various elements comprising the invention, reference being had to the accompanying drawings forming a part hereof, wherein:

Figure 1 is a front elevational view of a 30 door equipped with my invention,

Figure 2 is a side elevational view showing the connection provided for the hand operated lever,

Figure 3 is a similar view of the guide roller 35 mounted at the lower edge of the door,

Figure 4 is a perspective view of the rock shaft with its lever arranged at the top of the door,

40 Figure 5 is a vertical transverse sectional view through the door,

Figure 6 is a fragmentary sectional view of the upper edge of the door showing one of the brackets provided for attaching the rock

45 shaft thereto,

Figure 7 is a sectional view of the door taken along a line 7—7 of Figure 1,

Figure 8 is a fragmentary detail of one of the door rollers,

50 Figure 9 is a view in elevation showing the

vehicle wheel operating in connection with the door when used as a garage door and

Figure 10 is a perspective view of the vehicle wheel crank lever.

Referring to the drawings in detail, my invention comprises a door composed of upper and lower sections 5 and 6 respectively hingedly connected with each other permitting upward swinging movement thereof enabling the sections of the door to be folded into a horizontal position above the doorway as shown by the dotted lines in Figure 5.

55 The door is supported upon a rock shaft 7 secured along the upper edge of the upper section 5 of the door by brackets 8, the end of the shaft 7 may be journaled for rotation at the opposite side of the door frame 5.

60 The inner surface of the vertical side members 10 of the door frame is provided with vertically extending grooves 11 constituting 70 a guideway for the roller 12 mounted at each side adjacent the lower edge of the lower door section 6.

65 One end of the rock shaft 7 is provided with a bell crank 13 having one arm thereof 75 connected to a vertically extending link 14, the lower end of which is attached to one end of a pivotally mounted manually operable lever 15. The opposite arm of the bell crank 13 is attached to the upper end of a vertically 80 disposed rod 16, the lower end of said rod being attached to a coil spring 17 secured to a stationary part of the door frame adjacent the lower end thereof. Between the rods 16 and spring 17 is also interposed a turn buckle 85 18 providing for the proper tensional adjustment between the spring and the rod.

80 At the end of the rock shaft 7 opposite from the bell crank 13 is mounted a lever 19 disposed in the same relative position with respect to the rock shaft as the arm of the bell crank to which the rod 16 is attached. The lever 19 forms a connection with the upper end of a rod 20 of an identical construction as the rod 16 and also having a 90 spring 21 and turn buckle 22 arranged at its lower end for attachment to a permanent part of the door frame.

95 As will be observed from an inspection of Figure 2 of the drawing the bell crank 13 is 100

arranged with its arm to which the rod 16 is attached adapted to swing over the center of the rock shaft 7 during the movement of the sections of the door into their upper positions by the actuation of the bell crank to the operation of the lever 15. By arranging the bell crank in this manner the springs 17 at the opposite sides of the door are capable of exerting sufficient force upon the bell crank 5 to prevent the lowering of the sections of the door through the weight thereof. In order to form a positive connection between the rock shaft 7 and the upper section 5 of the door, a bolt 23 is inserted transversely through 10 the rock shaft with its end extending through 15 the bracket 8 provided for attaching the rock shaft to the door.

In Figures 9 and 10 of the drawing I have illustrated a connection adapted for actuation 20 through engagement with the wheels of a vehicle for operating the rock shaft so as to cause the raising or lowering of the door. This form of the invention comprises the use of a vertically disposed link 24 having its 25 upper end attached to one of the arms of the bell crank and with its lower end attached to an arm of the bell crank 25 pivotally mounted adjacent the lower end of the door frame. The opposite arm of the bell crank 30 25 is attached to one end of a horizontally disposed operating rod 26 extending outwardly in a direction in front of the door with its outer end attached to a lever 27 formed on one end of a crank rod 28. The rod 28 35 is disposed transversely across the driveway in front of the door and on which is formed a pair of offsets 29 in the form of cranks, said offsets being disposed on the crank rod substantially at right angles to 40 each other. Thus when one of the offsets is arranged in a vertically extending position, the other offset will be disposed horizontally. The offsets 29 are arranged so as to protrude above the surface of the driveway and 45 adapted for engagement by the wheels of a vehicle indicated by dotted lines in Figure 9 of the drawing and identified by the numeral 30, and upon such engagement the force of the wheel will operate to push the offset 50 into a horizontal position thereby operating the lever 27 and through the rod 26 to operate the bell cranks 13 and 25 so as to cause the raising or lowering of the section of the door, as the case may be, depending upon 55 the direction in which the vehicle is moving.

A manually operable connection may also be provided in conjunction with the vehicle wheel operating connection, such manual operating means comprising a lever 31 pivotally 60 mounted to the door frame and to which a link 32 is attached forming a connection with the arms of the bell crank 13 to which the link 24 of the vehicle operating connection is also attached. In this construction a coil spring 65 33 may be substituted for the rod 16, turn

buckle 18 and spring 17 as shown in Figure 2 of the drawings for engagement with the opposite arm of the bell crank 13 so as to secure the section of the door in upward folding position.

It is obvious that the invention is susceptible of various changes and modifications, without departing from the spirit or scope of the invention or sacrificing any of its advantages, and I accordingly claim all such forms of the device to which I am entitled. 70 75

Having thus described my invention, what I claim as new is:

1. In a device of the class described comprising a vertically suspended door mounted for upward swinging movement, a rock shaft journaled to a supporting structure at the opposite side edges of the door and fixedly secured to the upper edge of the door, a bell crank carried at one end of said rock shaft, 80 an operating lever operatively connected to one of the arms of the bell crank and means connected with the opposite arm of said bell crank for securing the door in uppermost position.

2. In a door operating device of the class described comprising a door composed of hingedly connected upper and lower sections adapted for upwardly swinging movement into a horizontal position, a rock shaft secured to the upper edge of the door having its end journaled for rotation in the opposite side of the door frame, a bell crank formed at one end of said rock shaft, an operating lever operatively connected to one of the arms of said bell crank and adapted through its actuation to cause the rotation of the rock shaft whereby to raise the sections of the door, a rod attached to the opposite arm of said bell crank and a yieldable connection for said rod adapted to respond to the movement of the bell crank during the upward swinging movement of the door and to releasably secure the bell crank against operative movement when the door is disposed in uppermost position. 90 95 100 105 110

3. In a door operating device of the class described comprising a door composed of hingedly connected upper and lower sections adapted for upward swinging movement into a horizontal position, a frame for the door having vertically disposed guides formed therein, rollers mounted at the lower edge of the lower section of the door arranged for vertical movement in said guide, a rock shaft attached to the upper edge of the door with its ends journaled for rotation in said door frame, a bell crank carried at one end of the rock shaft with its arm disposed in upwardly oppositely inclined position, operable means for said rock shaft comprising a manual operable lever pivotally mounted adjacent the lower edge of the door, a link connecting said lever to the outwardly inclined arm of said bell crank, vehicle operating means for said rock shaft comprising a crank lever disposed 115 120 125 130

transversely with respect to the path of the vehicle and arranged for actuation by contact with the wheels thereof, rods connecting said crank lever with the outwardly extending arm of the bell crank, and a rod attached to the opposite arm of the bell crank having a yieldable connection with a stationary part of the frame and adapted to retain the door in its upward position.

10 4. A door operating device of the class described comprising a vertically suspended door mounted for upward swinging movement, a rock shaft attached to the upper edge of the door and extending transversely of the door opening with its ends journaled in a supporting structure at the sides of the door, a bell crank carried at one end of said rock shaft, manually operable and vehicle engageable operating means for said rock shaft arranged for the selective actuation thereof and attached to one of the arms of the bell crank, said last named arm of the bell crank being normally inclined upwardly at one side of the vertical plane of the rock shaft 25 when the door is closed and adapted to be moved to a position at the opposite side of the vertical plane of the rock shaft when the door is opened, and yieldable means attached to said last named arm and operable to yieldably 30 retain the door in either position.

In testimony whereof I affix my signature.
ALFRED C. FARR.
